PROCESS FOR OBTAINING VALUABLE DISTILLATES FROM CARBONACEOUS MATERIALS

Robert P. Russell, Baton Rouge, La., assignor to Standard-I. G. Company

Application January 22, 1929. Serial No. 334,148

5 Claims. (Cl. 196—56)

The present invention comprises an improved process for obtaining valuable low boiling oils from carbonaceous materials such as petroleum, tars and the like and also from solid carbonaceous materials especially those, which like coal, contain solid foreign matter. My process will be fully understood from the following description and the drawing.

The drawing is a semi-diagrammatic view in sectional elevation of an apparatus constructed according to my invention and indicates the flow of materials.

Referring to the drawing, reference numeral 1 denotes a pipe coil arranged in a suitable furnace setting 2 and adapted to heat a stream of hydrocarbon oil or the like to an elevated temperature. The coil discharges into a reaction chamber 3 which is constructed to withstand high internal pressure and high temperature, as well as the corrosive effects of the reactants. The contents of the drum is kept in thorough agitation by means of a stirrer 4 or the like and the temperature of the drum is maintained at the desired level in any suitable manner, for example, by the use of internal electrical heaters, but I prefer to continuously withdraw a part of the oil by pipe 5 and circulate the same by means of a suitable pump 6 back to drum 3 by way of coil 1. Hydrogen or a gas rich in free hydrogen is withdrawn from a suitable source (not shown) by pipe 7, compressed by a compressor 8 and then conducted by pipe 9 to a feed manifold 10 from which a part may be forced into the inlet of coil 1 by line 11 and the remainder introduced directly into drum 3 by line 12. The drum is preferably protected against excessive loss of heat as by insulation 13.

Vapor from drum 3 is conducted by vapor line 14 to a heat exchanger 15, then to a condenser 16 and gas separator 17. Distillate is conducted to storage (not shown) by pipe 17' while gas is recompressed by booster pump 18 and returned to hydrogen manifold 10 by pipe 18'. The gas may be purified before return to the manifold, for example, by washing with an aqueous soda solution to remove hydrogen sulphide and then with oil to remove gaseous hydrocarbons.

A part of the oily mass undergoing treatment is withdrawn from drum 3, preferably in a continuous stream, by a line 19 which is fitted with a pressure reduction valve 20 and is discharged into a chamber 21. Chamber 21 may be of any suitable form, with or without baffles 22, but with a lower chamber 23 which is furnished with a double bell closure 23' or other suitable means

for discharging solid or semi-solid materials intermittently. A vapor pipe 24 conducts vaporized oil to condenser 25 and discharges it into a separator 26 from which gas is removed by vacuum pump 28. Condensate is withdrawn from separator 26 by pump 29 and is returned to drum 4 as will be described below. A current of inert gas may be passed into drum 21 by pipe 21a in order to assist in the vaporization of the liquid after reduction of pressure.

Fresh oil is drawn from storage (not shown) by pump 31 and a part may be diverted through a pulverizer 32 in which coal or other solid carbonaceous material is reduced to a finely divided state and thoroughly incorporated with the oil. Condensate from drum 26 is forced by pump 29 through a line 30 into a branch pipe so that it may be passed through pulverizer 32 or may be added to the mixture of oil and coal as shown in the drawing. In any case the mixture is then forced through heat exchanger 15 to coil 1 by line 34.

In the operation of my process, crude oils, tar and the like may be used as the base and carbonaceous material which contains ash or other foreign solid impurities is suspended in the oily liquid. Such material is subjected to the action of a gas rich in free hydrogen under a high pressure, for example, above about 25 atmospheres and preferably at 100 or 200 atmospheres or higher. The body of material which is in a semi-liquid, at least pumpable form, is maintained at a temperature within the approximate range of 750 to 850 degrees Fahrenheit. Hydrogen is continuously forced into the body of oily material and vapor which comprises distillate and gas is continuously removed during the hydrogenation.

Part of the oily mixture is withdrawn from drum 3 and discharged into a chamber 21 which is maintained at a pressure considerably lower than drum 3. By this means, a large part of the oil withdrawn is vaporized and separated from solid matter, such as ash, free carbon, unvaporizable asphaltic residue, and the like. The distillation is preferably done under vacuum and the solid matter may be obtained in substantially dry form, at least, freed from the majority of the oil which is condensed and preferably returned to the body of material undergoing hydrogenation in drum 3.

When a relatively large proportion of coal is used with the oil, the reaction is strongly exothermic and furnishes sufficient heat to maintain temperature in the drum without internal heating or the like, and coil 1 may be used merely

as a preheating coil for the fresh suspension of carbonaceous material in oil. It will be understood that, if desired, fresh oil need not be continuously supplied; but after the cycle has been established, heavy oil may be produced in sufficient quantity to furnish the suspension medium for the entire quantity of coal or other carbonaceous material heated.

My invention is not to be limited by any theory of the process, nor by merely an illustrative example, but only by the following claims in which I wish to claim all novelty inherent in the invention.

I claim:

15. 1. An improved process for production of low boiling liquid hydrocarbons from solid carbonaceous materials comprising, forming a suspension of finely ground carbonaceous material in heavy oil, maintaining a body of the suspension at a 20 decomposition temperature and under high pressure, continuously forcing a hot mixture of the suspension and a gas rich in free hydrogen into the body, continuously withdrawing vapor therefrom, condensing low boiling liquid hydrocarbon 25 from the vapor, separately withdrawing a part of the suspension from the body, reducing pressure on the part thus withdrawn whereby substantially all of the oil is vaporized, condensing the vapor and returning a part of the condensate to the body of the material undergoing 30 treatment.

2. Process according to claim 1 in which the suspension of solid material in oil is maintained at a temperature of approximately 750-850 degrees Fahrenheit and under pressure in excess of 25 atmospheres.

3. In a process for the liquefaction of coal the steps of maintaining a body of finely divided coal suspended in heavy oil at high temperature and 40 under high pressure of hydrogen, continuously

removing the vapors evolved therefrom, separately withdrawing a part of the suspension containing ash, reducing pressure on the part withdrawn whereby the liquid is substantially completely vaporized, separately condensing this vapor and returning the condensate to the body of coal and oil.

4. An improved process for producing valuable liquid hydrocarbons from solid carbonaceous material which comprises reducing such material to a finely divided state, suspending the same in heavy hydrocarbon oil, maintaining a body of such suspension at an elevated temperature and under high pressure in contact with a gas rich in free hydrogen, continuously removing vapors from the body of suspension, separately withdrawing a part of the suspension from the body, reducing pressure on the part withdrawn whereby a substantial portion of the hydrocarbon liquid is vaporized, passing a current of inert gas through the residue after reduction of pressure, and separately condensing the vapor evolved by the reduction of pressure.

5. An improved process for producing liquid hydrocarbons from solid carbonaceous material which comprises reducing such material to a finely divided state, suspending the same in heavy hydrocarbon oil, subjecting a body of such suspension to the action of a gas rich in free hydrogen at an elevated temperature and under high pressure, continuously removing vapors from the body of suspension, separately withdrawing a portion of the suspension from the mass undergoing hydrogenation, reducing pressure on the portion withdrawn to a sub-atmospheric pressure whereby a substantial portion of the hydrocarbon liquid is vaporized, and separately condensing the vapor.
